FRANÇOIS ROCHEFORT, OF PARIS, FRANCE.

ROTARY MOTOR.

Application filed February 25, 1919. Serial No. 279,200.

To all whom it may concern:

Be it known that I, FRANÇOIS ROCHEFORT, a citizen of the French Republic, and a resident of Paris, France, have invented certain new and useful Improvements in Rotary Motors, of which the following is a specification.

This invention relates to a polycylindrical rotary internal combustion motor, furnished with an annular body with rotating cylinders of circular form, in which the pistons which move are fixed to a single central piece in the form of Z, that moves in the direction of rotation of the cylinders at a variable angular speed.

According to this invention the movement of the central piece in the form of Z is effected through the medium of two pairs of toggle links, connected on the one hand with the cylinders and on the other hand with the said central piece, and having rollers bearing against two fixed twin cams. These latter are situated at opposite sides of the central plane of the annular body.

25 In the accompanying drawing given by way of example:—

Fig. 1 is a diagrammatic view of the motor, partly in section.

Fig. 2 is a similar view showing the movable parts in a different position.

Fig. 3 is a longitudinal section on a larger scale showing the working of the valves.

Fig. 4 is a similar section showing the cooling arrangement by the circulation of air.

40 This motor is composed of elements assembled in groups of two, each of which comprises two diametrically opposed cylinders C' and C² of circular section, each cylinder constituting a sector of about 70° of an annulus of circular cross section.

These cylinders are held in position at an uniform distance from the centre O of the motor by side cheeks F forming part 45 of a casing, the cheeks being mounted on ball bearings the interior rings of which are fitted under considerable friction on a fixed hollow shaft A about which the motor rotates.

50 The group consisting of the casing and cylinders can rotate freely around the fixed shaft and bears at H the coupling device by which the power developed may be transmitted to the machine or point where it is to be absorbed.

On the fixed shaft A two twin cams K

made of tempered steel having keyways corresponding to the shaft keys are non-rotatably mounted.

These cams which are of special profile, 60 are kept at a definite distance apart by the interposition of an annular oscillating bearing R' the interior rim or crown of which acts as a distance piece.

On the large rim of the oscillating bearing R' is mounted a central piece terminating in two diametrically opposed curved arms running in the direction of the motor the whole constituting a rigid piece in the 70 form of Z.

At the ends of the curved arms of the Z are rigidly fixed the pistons p' and p² which are furnished with packing rings or segments. These pistons adapt themselves to the curvature of the cylinders and can move 75 in the interior thereof, oscillating around the shaft A whilst remaining at an uniform distance from the centre O (Figs. 1 and 2.)

The driving connection between the pistons and the shaft A is formed by two 80 diametrically opposite groups of toggle links, each comprising a link B and a link B'.

Each link B is mounted to oscillate 85 around a shaft X' carried in bearings in a triangular bracket T formed in one piece with the cylinder and serving for centering and fixing it to the cheeks F.

The opposite end of each link B is arranged to engage a short shaft X.

The pair of parallel links B' also engage the short shaft X and are held in position one on each side of the link B by anti-friction rollers R² whose inner bearing rings are locked in place upon the ends of the 90 shaft by nuts e as shown in Fig. 4.

The opposite ends of the parallel links B' are fixed under considerable friction on the shoulders of a short shaft X² the central part of which oscillates in a bearing in the 100 central piece Z.

The arrangement of the two opposed groups is identical.

If the group of cylinders and casing be 105 rotated in the direction of the arrow the shafts X' rotate at an angular velocity equal to that of the cylinders around the centre O through rigid connection with the fixing and actuating parts T.

The rollers R² are actuated by the links B and the shafts X² through the medium 110 of the parallel links B'. The shafts X²

actuate through connection the central piece Z which compels the rigidly connected pistons p' and p^2 to move at a speed which is at first equal to that of the cylinders.

5 If an elastic resistance be interposed in one of the two cylinders say C' between the end of the cylinder head and the piston the cylinder will have a tendency to move in the direction indicated and the piston in 10 the reverse direction. The effect of this is to apply tension to the links B , B' and in consequence cause the rollers R^2 to press in a radial direction upon the cam K .

15 The rollers R^2 are thus kept pressed against and caused to follow the path of the twin cams K .

Starting from the points N , N' , the rollers R^2 following the profile of the cams are moved away from the centre of the motor.

20 The group of cylinders and casing moving at a rotary speed which may be regarded as practically uniform the rollers R^2 and consequently the shafts X move away from the centre of the motor; the result of which 25 is that the shafts X' and X^2 come near to one another which causes an increase in the rotary speed of the pistons and consequently brings them nearer the ends or heads of the cylinders. When the rollers R^2 are at 30 M and M' that is to say at the peaks of the cams, the pistons are at the end of their stroke in the direction of the cylinder heads Q at inner dead centre.

35 The two pistons act simultaneously in their respective cylinders.

Supposing that during this stroke towards the cylinder head, hereinafter referred to as the ascending stroke, the piston p^2 has compressed an explosive mixture and 40 after having passed the inner dead centre, ignites this mixture so as to receive an impulsive expansion.

The forces previously indicated having increased in value the general resultants 45 tend to throw the shafts X towards the centre of the motor. But these shafts cannot move freely being guided by the rollers R^2 which are always forced to roll on the cams the profile of which starting from the 50 points M and M' constitutes approximately a descending curve having the shaft X^2 as centre.

Under the action of the resultant forces 55 the rollers and consequently the shafts X describe a curve around the centre of the shafts X^2 following the outline of the cams K which are fixed upon the stationary shaft A .

At this moment the shafts X^2 are thus 60 almost stationary and consequently the central piece Z ; in consequence of which the pistons are also almost stationary and therefore serve as points of support to the expanding gases. The cylinders and casing 65 block being free to move, increases its ro-

tary speed and takes up the largest part of the energy furnished by the expansion of the gases.

Starting from a certain point the cam slope becomes tangential to the circumference passing through the point where the rollers R^2 come nearest to the centre of the motor at N and N' .

The rollers engage on this slope and move away from the primitive position of the 75 shafts X^2 forcing these latter to move in the direction of rotation of the whole with increasing speed which becomes equal to that of the cylinders when the rollers pass at N and N' and greater from those points 80 up to M and M' .

If we take again the movement at N and N' Fig. 2, we see that a complete ascending stroke of the pistons is equal to 60° of movement of the pistons in the cylinders and 85 90° of movement of the cylinders around the centre O , the pistons having moved 90° and $60^\circ=150^\circ$ around the same centre.

The pistons having passed the inner dead 90 centre, become stationary for a certain time and the descending stroke then takes place through the continuous movement of the cylinders. The pistons then move, but at a less speed than that of the cylinders up to the outer dead centre. 95

A second stroke of the pistons is effected after 90° of rotation of the cylinders the pistons also move in the same direction but only 30° remaining in arrear 60° .

Thus in this half rotation the cylinders 100 have moved 90° or 180° and the pistons 150° and 30° or equally 180° .

The second half rotation is effected in the same manner.

The cylinders move again twice $90^\circ=180^\circ$ 105 and the pistons 150° during one stroke and 30° during the other, which together make 180° around the centre O .

Each piston having run four strokes in 110 its cylinder during one complete revolution of the motor, the cycle is completed.

In looking at Figs. 1 and 2 it will be seen that when the cylinder C' is in expansion stage the cylinder C^2 is in the admission stage.

When the cylinder C' is in the exhaust stage, the cylinder C^2 is in the compression stage.

When the cylinder C' is in the admission stage C^2 is in the expansion stage. 120

When the cylinder C' is in the compression stage C^2 is in the exhaust stage.

In an element of two opposite cylinders the expansions follow one another at intervals of 180° . 125

Thus double regularity for the same number of cylinders comparatively to an ordinary motor.

Distribution (Fig. 3).—The complete cycle being effected in one rotation of the 130

motor the distribution devices must act in each cylinder once in each revolution.

For this purpose the valve operating device moves at a rotary speed equal to that of the cylinders and once in each revolution passes in front of a fixed cam K' which is held locked on the shaft A.

This kind of motor may have 1, 2, 3, or 4 groups of two elements on a single shaft comprising say: 4—8—12 or 16 cylinders.

The motor indicated has two groups of two elements viz:—8 cylinders.

The cams are so mounted on the fixed shaft A as to enable the motive expansions to be distributed throughout the rotation at intervals equal to 45° in the 8 cylinder motor.

A cam K' locked upon the stationary shaft A alternately raises the valve actuating rods t which are furnished with rollers q and are arranged to control the valves S through the medium of levers q.

A very weak spring s normally tends to close each valve at the starting of the motor. When the motor is running the closing is assured by the centrifugal force acting on the body of the valve.

The actuating rods t are moved towards the centre of the motor by the centrifugal force acting upon the valve bodies and upon counterweight situated opposite the rods on the levers q.

Air supply.—The cylinders C' and C² are extended by sheet iron tubes V put together in halves and forming a shield. This arrangement enables the oil to be caught when it is in excess and is projected towards the exterior from all the devices in movement in the interior of the motor. These tubes are open towards the interior of the motor so as to allow a free passage for the arms of the Z piece carrying the pistons, and terminate in suction pipes u which establish communication between the valve boxes and the interior of the tubes.

In order that the oil accumulated within the shields or tubes by centrifugal action may not enter the cylinders the suction pipes are each furnished internally with an oblique partition C'.

The interior of the motor casing is in constant communication with the open air through openings o Fig. 4 drilled laterally in the cheeks F towards the centre of the motor.

The cylinders are furnished with vanes for the cooling. Each of them has an attached head Q furnished with an admission valve S of large diameter. This head is mounted on a fitting containing a suitable joint and secured by four nuts.

Exhaust openings or ports L formed at the outer end of the cylinder are uncovered by the piston at the end of its exhaustion stroke at the outer dead centre.

These ports run into an expansion chamber w fitted and maintained by tightening on the outside of the cylinder. This chamber is placed in the reverse direction to the rotation of the motor in order to increase 70 the rapidity of flow of the gases passing into the interior. It has externally cast vanes w' for the cooling.

Supply of combustibles.—This motor is a high compression motor, the air alone is 75 drawn by suction into the cylinders and powerfully compressed so as to raise the temperature sufficiently to allow of the ignition of the combustible vapours which are injected under pressure into the cylinders 80 by independent piston pumps rotating with the motor.

Practical cycle-working (Figs. 1 and 2).—Let us consider a single element formed by two diametrically opposite cylinders. 85 The phenomena occur identically in each of them but at an angle of 180° in relation to the rotation of the motor.

Admission of air.—Let us cause the motor to rotate in the direction of the arrow until its piston is at the end of the course at inner dead centre. The valve being open there is communication between the interior of the cylinder C' and the casing through the suction pipe U.

Let us continue the rotation. The relative vacuum caused by the movement of the cylinder causes a volume of cold air to come in from the casing which latter is in constant communication with the open air 100 through the openings o, Fig. 4.

Thus at this movement there exists in the admission pipe a current of air the velocity of which increases rapidly in consequence of the linear velocity of the piston. This 105 linear velocity diminishes in value until it reaches zero. At this moment the exhaust openings L are freed by the piston and establish communication with the chamber w where a depression prevails resulting 110 from its movement. This depression assists the vacuum previously produced by the piston and enables the body of air entering the cylinder at considerable velocity to continue its movement through the interior of 115 the cylinder until the exhaust ports are reached.

At this moment the velocity of the air reaches its maximum value and one quarter revolution of the motor say 90° is effected.

End of admission—Compression of pure air.—The motor continuing its movement the piston increases its angular velocity and covers the exhaust openings L. The body of air impelled at a great velocity continues 125 its movement by reason of its inertia and accumulates in the cylinder until the internal pressure becomes sufficient to cause it to lose its velocity. At this moment the valve closes.

The piston continuing its movement approaches the head of the cylinder. The compression of the air begins and attains its maximum value when the piston moves to the inner dead centre.

At this moment the motor will have rotated a further 90° in all say 180° .

Ignition and expansion. Exhaust of the consumed gases.—At this moment the compression of the air is such that its temperature is sufficient to ignite the combustible vapours injected into the cylinder. This injection commences slightly before the piston reaches the inner dead centre and terminates shortly afterwards.

- 10 The combustible being injected gradually under pressure and vaporized on its entry into the chamber the ignition is very rapid the combustion begins, and considerably 20 raises the temperature of the air compressed in the cylinder consequently its pressure increases rapidly to a degree which is limited and is kept uniform during a fraction of the stroke of the piston.
- 25 This method of injecting the combustible makes it possible to avoid a violent and breaking strain on the piston and the cylinder thus reducing the stress on the devices: connecting links, cams, and bearings. The 30 mean pressure is as high as in an explosion motor but the expansion is gentler imparting greater suppleness to the motor.

- 35 The question is not the forming of a more or less perfect gaseous mixture in order to effect its rapid ignition and a satisfactory expansion but simply the regulating of the quantity of combustible injected in order to ensure a more or less powerful expansion with the pressure retaining an almost 40 uniform value.

The maximum quantity of combustible to be injected is limited by the quantity of oxygen contained in the cylinder.

- 45 At the beginning of the expansion the piston is made stationary in consequence of the resistance offered by the cams K to the rollers of bearings R².

- 50 The cylinder receives tangentially the stress resulting from the expansion of the gases. This stress may be considered as applied to a lever whose length is equal to the radius joining the centre of the motor and the centre of the interior section of the cylinder.

- 55 After a certain movement of the cylinder during the impulsive expansion the piston begins to move and acquires an acceleration of rotation which is less than that of the cylinder until the latter has moved 90° starting from the inner dead centre.

A little in advance of the outer dead centre, the piston frees the exhaust openings L, the section of passage of which is very great.

60 The consumed gases being still at a rela-

tively high pressure above that of the atmosphere pass through the openings L and expand in the open air flowing through the exhaust chamber w in a direction opposite to the direction of rotation of the motor 70 in order to facilitate the discharge and to obtain a useful reaction of the gases.

The expansion velocity of the consumed gases owing to the pressure at the opening of the ports, and to the arrangement and section of the passage, is high. A very rapid decrease of pressure and of temperature is produced which causes considerable depression in the cylinder.

In order to avoid the return of consumed 80 gases to the cylinder, the admission valve opens rapidly presenting a large section of passage enabling the cold air driven by the centrifugal force against the inside of the casing to fill up the relative vacuum produced in the cylinder. This body of air follows the burned gases and passes through to the exhaust chamber w. The object of the chamber w is to prolong the depression in the cylinder caused by the rapid expansion 85 of the gases.

The result is a forcible current of cold air in the interior of the cylinder cooling the sides and expelling the burned gases.

The velocity of this current of air may 90 be made very great by precisely regulating the point at which the admission valve is opened. It will be seen that the period during which the gases burned at a high temperature are in contact with the sides 100 of the cylinder and of the piston is reduced by this powerful scavenging action to the minimum; the quantity of heat taken up by the sides is much less and consequently the mean temperature is reduced $\frac{3}{4}$ of a revolution. 105

Clearing out of the combustion chamber and exhaust of hot air.—The motor acts like a fan of considerable capacity and during the period when the ports L are opened the 110 air taken from the casing is replaced by an equal quantity coming from the atmosphere. The motor continuing to rotate the piston commences its ascending stroke and covers the exhaust openings.

In consequence of its inertia the body of air projected at great velocity continues to penetrate into the cylinder the valve remains completely open the pressure increases slightly in the cylinder until the 120 velocity of the produced current is nullified the air then expands and being forced by the piston returns to the casing passing around the valve that is always completely open.

A certain quantity of heat taken up in coming in contact with the sides is carried off by this body of air expelled from the cylinder by the piston thus the exhaust period here is a cooling period.

When the piston is at the inner dead centre the cylinder has completed the last quarter of a revolution. It is at the starting point having completed the cycle in a single revolution. The same is the case with the cylinder C².

When one of the cylinders exhausts the hot air in the casing the opposite cylinder compresses a charge of air.

The consumed gas discharged through the exhaust ports L behind the pistons is drawn along by the depression in the chamber w and is also driven by the pressure of air tending to enter the cylinder from the interior of the casing. This body of hot air is replaced in the casing by a quantity of cold air coming from the interior. There is always a current of air in the interior of the casing which acts as a centrifugal fan.

When the ports L are covered by the pistons the body of air in motion continues to accumulate in the cylinder in consequence of its inertia.

Starting.—In order that the compressions may be very forcible at starting the starting is effected automatically by an admission of compressed air into the cylinders which are at the expansion stage and the pistons of which have passed the inner dead centre in the direction of rotation.

Cooling. Special arrangements. Circulation of air.—Each group of two elements, having four cylinders in all is enclosed by a casing V in the form of a drum made of sheet aluminium having vertical partition c between the two elements. These drums are firmly connected with the outer cylindrical casing E also made of aluminium. The whole is kept fixed and perfectly concentric to the motor.

In the case of an aviation motor the interior of the casing E is in communication with the open air so that air may be delivered to the motor by the propeller.

The interior drums V communicate by means of pipes b' with an exhaust chamber W which opens into the atmosphere by way of the circular casing E.

This exhaust chamber W would be arranged on an aviation motor in the space existing between the casing E and the hood of the apparatus. It should be closed in front and in communication with the open air through wide openings formed in the direction opposite to that of travelling so as to obtain a slight depression in the interior.

Circulation.—Let us put the motor in motion. The body of air in contact with the sides in movement is thrown by the centrifugal force against the interior sides of the drums tangentially to the exterior of the movable part of the motor which acts as a fan.

The air thus compressed finding no outlet except the pipes b' rushes into them

creating behind it and towards the centre of the motor a zone of depression. This relative vacuum is relieved by air coming from the interior of the casing E and passing around the drums.

The tubes in extension of the cylinders are very smooth and rather small in diameter thus leaving a space sufficient for the passage of cold air, into which the cylinders furnished with longitudinal vanes plunge. 75 These vanes are very high so as to increase the radiation surface.

After coming in contact with the sides and the vanes of the cylinder the air is projected towards the pipes creating a continuous current carrying along the burned gases as well as the air coming after each exhaustion or termination of admission from the interior of the cylinders through the expansion chambers.

The circular velocity of the cold air results from the rotary speed of the motor and may be very considerable.

The circulation of cold air is equal and uniform for all the elements whatever their rank in the motor.

The outer casing of the exhaust chamber is formed of a metal tube which is a good heat conductor. It transmits a certain quantity thereof to the open air.

The successive scavenging actions in the interior of the cylinders reduce the period during which the sides are heated and cause a very active internal circulation of air cooling the cylinders, valves and pistons and increasing the circulation of air outside.

The cooling is extremely powerful and can be regulated by varying the section of passage at the entrance to the circular casing E.

The linear velocity of the pistons (relative velocity with relation to the cylinders) is at the maximum when the rollers R² having passed the points M travel along the descending portions of the cam path.

Instead of being completely stationary at this moment, in practice the pistons are almost stationary, but they never move in the direction opposite to the rotation of the motor. The profile of the cams K in moving downwards from the point M takes a slightly eccentric position coming away from the point in which the centre of the shaft X² lies at the moment when the rollers R² move to M.

This linear velocity of the pistons with respect to the cylinders is equal to zero when cylinders and pistons move at the same rotary speed around the centre O.

The rotary speed of the pistons reaches the maximum when the rollers R² move through the arc N, M of the cams K.

When the rollers R² reach M the inertia of all the moving parts such as connecting links, bearings, rollers, Z shaped pieces and pistons, attain the maximum value.

This inertia which is very considerable is absorbed by the resistance of the gases the pressure of which increases rapidly to the inner dead centre, and only adds to the value 5 of the motive effort which constitutes an appreciable advantage from the mechanical point of view.

Whatever may be the strokes or the positions of the cylinders the rollers R^2 remain 10 in constant contact with the cams K .

When the ports L are opened the fall of pressure is gradual and the various moving parts of the mechanism having an accelerated movement their inertia comes into action 15 in a useful manner offering resistance preventing the rollers from leaving the cams.

When the orifices are closed there is always a flexible resistance on one of the pistons 20 compression or motive expansion.

The centering of the pistons can be perfect in consequence of their rigid connection with the central piece mounted on an oscillating bearing.

25 The pistons are subjected to a tangential stress which in consequence of the rigidity of the arms of the Z does not produce any normal reaction in the sides of the cylinder.

This allows of very great lineal velocities 30 being attained with minimum friction thus facilitating the lubrication of the cylinders.

The friction of the piston rings is limited by their elasticity. When the pressures and the temperatures are at the highest the pistons 35 being nearly stationary in space the centrifugal force has no action on the rings and thus does not impair their tightness. These rings which are very thin are grouped in twos and mounted so that their common 40 plane of contact passes through the radius of the motor.

The centrifugal force acting on the rollers R^2 as on the balls of a governor assist in the acceleration of the movement of the pistons, through the medium of the toggle links 45 B, B' at the moment when they should attain the maximum rotary speed and the losses of energy due to the inertia of the central Z piece being thereby reduced.

50 The toggle links always work tractively. The mechanical output of this motor can thus be very great and also the thermic output and consequently the total output.

I claim:—

1. A polycylindrical internal combustion 55 rotary motor comprising pairs of curved cylinders diametrically disposed with reference to a central stationary shaft about which the motor rotates, pistons operating in said cylinders, Z -shaped central pieces 60 carrying said pistons and rotatable about said shaft, pairs of diametrically opposed toggle links connecting the Z -shaped pieces with the cylinders, stationary cams mounted on the central shaft, and rollers mounted 65 on the toggle joints of the toggle links, said rollers bearing freely on the exterior running surfaces of the stationary cams and following the profile thereof.

2. A polycylindrical internal combustion 70 rotary motor comprising pairs of curved cylinders diametrically disposed with reference to a central stationary shaft about which the motor rotates, pistons operating in said cylinders, Z -shaped central pieces 75 carrying said pistons and rotatable about said shaft, pairs of diametrically opposed toggle links connecting the Z -shaped pieces with the cylinders, stationary cams mounted on the central shaft and disposed on each 80 side of the median plane of the cylinders, rollers mounted on the toggle joints of the toggle links, said rollers bearing freely on the exterior running surfaces of the stationary cams and following the profile thereof. 85

3. A polycylindrical internal combustion rotary motor comprising pairs of curved cylinders diametrically disposed with reference to a central shaft about which the motor rotates, expansion chambers connected with 90 the cylinders and arranged at the periphery of the motor in a direction opposite to that of the rotation of the motor, pistons operating in said cylinders, Z -shaped central pieces carrying said pistons and rotatable about said shaft, pairs of diametrically opposed toggle links connecting the Z -shaped pieces with the cylinders, rollers mounted on the toggle joints of the toggle links and stationary cams mounted upon the central 100 shaft, said rollers bearing freely on the exterior running surface of the cams and following the profile thereof.

In testimony whereof I have affixed my signature.

FRANÇOIS ROCHEFORT.
